SPRAYING MECHANISM

William H. Carrico, Detroit, Mich.

Application December 5, 1939, Serial No. 307,656

6 Claims. (Cl. 299—97)

This invention relates to improvements in spraying mechanism. It is illustrated as embodied in a portable spraying device of the type commonly used as a garden or flower spray. Obviously the invention might be embodied in spraying mechanism adapted for other uses.

An object is to provide spraying mechanism of simple and inexpensive construction which includes a tank adapted to carry a spraying liquid and pump mechanism associated with the tank and operable to withdraw spraying liquid therefrom and to discharge it as a spray where desired, and which pump mechanism is so constructed that the liquid contents of the tank is maintained constantly agitated during operation of the spray pump.

A further object is to accomplish such agitation and mixing of the spray liquid within the tank as to maintain it thoroughly mixed at all times by directing a spray of liquid under pressure from the pump outwardly over the floor of the tank sweeping therefrom any solid particles tending to settle thereupon and causing said solid particles to remain in suspension throughout the liquid within the tank. This also permits use of spraying materials which, because of the difficulty of maintaining a uniform suspension with ordinary equipment, are not susceptible to application by spraying except through use of this invention.

The construction is such that streams of agitating liquid shoot out over the floor of the tank in all directions during the operation of the pump and keep the mixture thoroughly agitated. Pump mechanism which differ in detail may be employed to accomplish this result and each embodies the invention here shown.

Two different modifications are illustrated in the drawings. In the primary modification the lower portion of the pump chamber constitutes the compartment within which pressure is imposed upon the liquid for spraying and the upper portion of the chamber constitutes the compartment within which pressure is imposed upon the liquid used for agitation purposes. In a second modification the pump mechanism embodies a primary pump chamber and a secondary pump chamber. Liquid is placed under pressure in the primary chamber for spraying purposes and liquid is placed under pressure within the secondary chamber for agitation purposes. Pressure is created in both chambers in response to the manual operation of a single operating handle.

In each of the forms shown the agitating streams or sprays are swept over the floor of the

10 tank at intervals in response to pump action. During movement of the pump piston in one direction these agitating streams are forced outwardly over the floor of the tank. When the piston moves in the opposite direction liquid is drawn into the pump. This stop and go method of agitation is particularly efficacious in maintaining uniform distribution of the suspended particles within the liquid and in preventing settlement thereof to the floor of the tank.

Other objects, advantages, and meritorious features of the invention will more fully appear from the following description, appended claims, and accompanying drawings, wherein:

15 Figure 1 is a perspective of a spraying outfit embodying my invention,

Fig. 2 is a vertical sectional view through the tank and through pump mechanism embodying my invention,

Fig. 3 is a sectional view through a tank and pump mechanism exhibiting a second modification of my invention, and

Fig. 4 is an enlarged sectional view through a 20 part of the structure of Fig. 3.

Spraying fluids which are used for garden and flower sprays and even for other purposes frequently comprise ingredients which should be maintained in suspension in the liquid vehicle and tend to settle out. A source of difficulty is 25 the maintaining of these particles uniformly distributed throughout the liquid so that the liquid will be uniformly effective. Various types of stirring devices have been provided for this purpose.

I propose to maintain the contents of the tank 30 in agitated condition by setting up a reciprocating movement of liquid over the wall or floor of the tank. This liquid movement sweeps in one direction in the tank and then reverses itself and sweeps in the opposite direction. I prefer to accomplish this movement of liquid by a spray of the liquid content of the tank outwardly away from the intake of the pump in all directions on one stroke of the pump and on the next pump stroke cause the movement of liquid toward the 35 pump intake. These features are exhibited in the structures shown and hereinafter described.

In Fig. 1 a tank indicated by the numeral 10 is 40 adapted to carry the liquid spray material. It is apparent that the tank may be of any particular shape and size. The one here shown is shaped to fit the body of an operator who would carry the same by straps 12 extending over the shoulders of the operator. The size and shape of the tank and the way in which it is carried have 45 nothing to do with the invention.

In the construction shown in the first two figures the tank 10 is shown as having a floor 12 provided with a sump 14. Pump mechanism is provided. It is here shown as embodying a pump chamber 16 threaded or otherwise secured to a reinforcing plate in the top of the tank. This pump chamber depends into the tank over the sump and has an intake 18 located within the sump. This intake is controlled by a valve 20. A foraminated element 22 superposes the valve to hold it in position. There is a pump piston 24 provided with cups 26 and with a handle 28 adapted to be grasped by the operator to reciprocate the piston. The upper end of the pump chamber is sealed by a cap 30 which forms a water tight seal. A gasket 32 may be provided as the upper portion of this pump chamber also constitutes a depression chamber.

Leading off from the lower end of the pump chamber is a discharge line 34 which delivers liquid to a compression chamber 36 through an intake controlled by the ball check valve 38 held to its seat by spring 39. There is a spray discharge line 40 which leads from a low point in the compression chamber and is fitted with any suitable type of nozzle such as 42 in Fig. 1 and with sufficient flexible hose to permit of direction of the spray as desired. In order to develop pressure in the compression chamber prior to use of the mechanism, the nozzle 42 may be equipped with a shut off valve as shown or other suitable means may be employed.

The pump chamber is provided at its lower end with a skirt 44 and there is an adjustable plate 46 which may be screwed on to the pump intake as shown in Fig. 2. The skirt may be serrated at its lower edge providing a plurality of discharge openings 48 and the plate 46 may be threadedly adjusted to diminish or enlarge the space between the plate and the skirt 44.

There is a by-pass 50 which leads from the upper end of the pump chamber to the space within the skirt 44. Through this by-pass liquid is delivered from the upper portion of the pump chamber to the space within the skirt 44.

In the operation of the pump, liquid is drawn into the pump chamber from the sump through the valve controlled intake 18 as the pump piston is elevated. Upon the down stroke of the piston this liquid is forced into the compression chamber 36. Upon such down stroke a depression is created above the piston within the pump chamber and into this depression liquid is drawn from the space within the skirt 44 through the by-pass 50. When the pump piston is again elevated it not only sucks a charge into the pump chamber through the intake 18 but it expels a charge through the by-pass 50 into the space within the skirt 44 from which space a plurality of fine sprays are directed outwardly and radially through the openings 48 to sweep over the floor of the tank. These openings are at approximately the level of the floor so that whatever suspended particles tend to settle upon the floor are swept up again into the liquid within the tank whereby that constant agitation of the spray liquid is maintained. This agitation is on a stop and go cycle so that it is particularly efficacious in maintaining the particles in suspension.

In the construction of Fig. 3 another type of spray pump is provided. This is conventional so far as the main pump chamber is concerned and the disposition of the spray line with respect thereto. In this construction the tank

again is indicated by the numeral 10. The main pump chamber is indicated by the numeral 16. It communicates with the tank through an intake line 17. The intake proper indicated by the numeral 18 is controlled by the ball check 20 held to its seat by a spring 21. The piston indicated at 23 is hollow. The handle 25 is mounted adjacent to the end of the piston and there is a spray head 27 mounted on the extreme end thereof. Liquid is taken into the piston through an intake 29 which intake is controlled by a ball check 31 held to its seat by spring 33. When the pump piston is reciprocated on its outstroke liquid is drawn into the pump chamber. On the in-stroke this liquid is forced under pressure into the hollow piston and therefrom through the spray head 27.

There is a second pump chamber indicated as 11. Within this pump chamber is a piston 13. Pistons 23 and 13 are both provided with conventional cups as shown. The pump chamber 11 communicates with the tank through a passageway 15. This passageway opens into the bottom of the tank as shown in Figs. 3 and 4. The bottom of the tank may be provided with an upwardly projecting boss 15' which is outwardly threaded and which is provided with a series of small openings 19 through its wall. A cap 19a is adjustably threaded upon this boss so as to control the extent of the passageways through said openings 19. The piston 13 in the secondary pump chamber 11 is coupled up through a link 13a with the handle 25 of piston 23 and in operation liquid is drawn through the passageway 15 from the tank into the secondary pump chamber 11 upon the withdrawal stroke of the piston and upon the compression stroke it is forced back under pressure through the passageway 15 into the tank to discharge over the floor thereof through the openings 19 in the boss 15'.

What I claim:

1. In spray mechanism; a liquid containing tank having a floor sump; a pump having a pump chamber provided at its lower end with an intake positioned within said sump, a pump piston within the chamber, a compression chamber communicating with the lower end of the pump chamber to receive liquid therefrom, a spray line leading from the compression chamber, a by-pass having one end communicating with the upper end of the pump chamber, and having its opposite end terminating on a chamber encircling the pump chamber intake and at approximately the level of the tank floor and provided with restricted liquid passageways adjacent the floor level through which liquid is drawn from the tank through the by-pass into the pump chamber above the piston upon its down stroke and through which liquid is discharged from the pump chamber through the by-pass into the tank upon the up stroke of the piston.

2. In spray mechanism; a liquid containing tank having a floor; a pump chamber provided with a valve controlled intake adjacent to the floor; a pump piston within the chamber, a compression chamber communicating through a valve controlled intake with the lower end of the pump chamber to receive liquid therefrom and provided with a spray discharge line, a skirt depending from the pump chamber surrounding the intake thereto, a by-pass communicating with the upper end of the pump chamber and communicating with the space within the skirt below the pump chamber, and means cooperating with the skirt and adjustable to provide a

controlled discharge for liquid urged through the by-pass into said space to flow outwardly radially therefrom away from the pump intake and substantially upon a level with the tank floor.

3. In spray mechanism, a liquid containing tank having a floor; a pump having a pump chamber provided with an intake positioned within the tank adjacent to the floor, a pump piston within the chamber, a compression chamber communicating with the lower end of the pump chamber below the piston to receive liquid therefrom, a spray discharge line leading from the compression chamber, a by-pass having one end communicating with the upper end of the pump chamber above said piston and having its opposed end terminating at approximately the level of the tank floor and provided with restricted liquid passageways adjacent the floor level through which liquid is drawn from the tank through the by-pass into the pump chamber above the piston upon its down stroke and through which liquid is discharged from the pump chamber through the by-pass into the tank upon the up stroke of the piston.

4. In spray mechanism, a liquid containing tank having a floor, a pump mechanism including a pump plunger and a pump chamber provided with an intake at its lower end within the tank adjacent to the floor and having a spray discharge line leading from such lower end below the plunger, said pump chamber having a second discharge line leading from its upper end above the plunger to a point at approximately the floor level to direct an agitating spray over the floor of the tank and adapted to receive therethrough liquid from the tank into the upper end of the pump chamber.

5. In spraying mechanism, a liquid containing tank having a floor, pump mechanism including a pump chamber having an intake within the tank at approximately the floor level, a liquid discharge line leading from the pump chamber, said pump mechanism including a secondary pump chamber communicating with the interior of the tank through a liquid passageway at approximately the floor level to draw liquid thereinto from the floor of the tank and adapted to discharge said liquid outwardly through said passageway over the floor of the tank, said pump mechanism including plunger means operable to draw liquid from the tank into said two pump chambers and to exhaust the first pump chamber through its discharge line and to exhaust the secondary pump chamber through said passageway directing an agitating spray over the floor of the tank.
6. In spray mechanism, a liquid containing tank having a floor, pump mechanism comprising two pump chambers and including plunger mechanism reciprocable within said chambers, each pump chamber having an intake communicating with the interior of the tank adjacent to the floor to receive liquid therefrom, one pump chamber having a liquid discharge outlet leading to the outside of the tank, the other pump chamber adapted to discharge its contents through its intake as an agitating spray over the floor of the tank, said plunger mechanism reciprocable within the pump chambers to draw liquid from the interior of the tank into each chamber and to exhaust the liquid independently from said pump chambers.
